Fred. D. Alling

United States Patent Office.

FRED. D. ALLING, OF ROCHESTER, NEW YORK.

Design No. 4,836, dated April 25, 1871.

DESIGN FOR AN INKSTAND.

The Schedule referred to in these Letters Patent and making part of the same.

To all whom it may concern:

Be it known that I, FRED. D. ALLING, of the city of Rochester, in the county of Monroe and State of New York, have invented and produced a new and original Design for Inkstands, of which the following is a specification.

General Description.

In the drawing—
Figure 1 is a perspective view.
Figure 2 is a vertical section.
A represents the inkstand.
The sides *a a a* are vertical planes, with the corners *b b b* rounded.

The top *c* is also made rounded or convex.

The bottom *d* is simply a triangular plane, which inclines downward from the rear to the front, where it forms an angle under the mouth or neck *f* of the bottle.

Claim.

What I claim, and desire to secure by Letters Patent, is—

The design for inkstand herein shown and described.
FRED. D. ALLING.
